UNITED STATES PATENT OFFICE

106,444

DESIGN FOR A PERFUME HOLDER

Joseph H. Kleckner, Chicago, Ill.

Application January 30, 1937, Serial No. 67,347

Term of patent 7 years

To all whom it may concern:

Be it known that I, Joseph H. Kleckner, a citizen of the United States, residing at Chicago, in the county of Cook and State of Illinois, have invented a new, original, and ornamental Design for a Perfume Holder, of which the following is a specification, reference being had to the accompanying drawing forming a part thereof.

The figure is a perspective view of the perfume holder showing my design.

The opposite side of the article is like the side shown, with the exception of a conventional ribbon bow which secures the flask in suspended position.

I claim:

The ornamental design for a perfume holder, substantially as shown and described.

JOSEPH H. KLECKNER.
